UNITED STATES PATENT OFFICE

JOHANN JACOB KEYSER, OF AARAU, SWITZERLAND

SPINNING AND TWISTING MACHINE

Application filed August 12, 1929, Serial No. 385,335, and in Germany and Switzerland November 5, 1928.

In my copending application Serial No. 250,259, filed January 28, 1928, I have disclosed certain improvements of spinning and twisting machines in which a spindle carrying beam is vertically reciprocated with relation to a stationary ring rail at a constant stroke and given additional movement at the stroke ends. In the embodiment shown in the said application the common operating shaft of the worm-actuated spindles carried by the spindle beam is rotated during its vertical reciprocations by a worm gear, whereby a desirable small supplementary rotation is imparted to the spindle operating shaft in opposite directions depending upon the beam performing its upward or downward stroke and tending to increase or decrease respectively the rotational speed of the said operating shaft. My present invention is concerned with a modification of the spindle actuating mechanism disclosed and claimed in the beforementioned application, according to which the spindle actuating shaft of the vertically reciprocating beam is operated by an endless sprocket chain likewise imparting a change in speed of rotation to the said actuating shaft when the beam is reciprocated.

In the drawing illustrating a preferred embodiment 10 designates the main shield or frame of a spinning or twisting machine on which a main sprocket wheel 11 is rotatably supported upon a shaft 12 and actuated by a sprocket chain 15 passing around the driving sprocket 14 of a main driving shaft 13, a tensioning sprocket 18 and upper and lower guiding sprockets 19. The sprocket chain is besides passed through a casing 16 integral with the spindle beam 8 and within which two guiding sprockets 17 and a sprocket 23 are located, sprocket 23 being mounted on the spindle actuating shaft 7 extending through the beam 8. The sprockets 19 are located vertically above and below the sprockets 17 respectively, as shown, so that the sprocket chain will be in engagement with a substantial portion of the peripheries of sprockets 17 and 23. The machine is further provided with a stationary ring rail and with means for effecting the vertical recipro-

cation of beam 8 and may also be provided with means for effecting additional vertical movements of the beam at the ends of its vertical reciprocations. All of these contrivances have not been illustrated in the drawing as they may be constructed in any known or suitable way and are as such not the objects of my present invention.

From the foregoing explanation it becomes apparent that, since the sprockets 19 do not partake in the vertical reciprocations of beam 8, also in this embodiment a supplementary rotation is imparted to the spindle actuating shaft 7 tending to increase or decrease the rotational speed imparted to it by the revolutionary movement of the sprocket chain around its vertically stationary sprocket. It will be noted that the spindle beam 8 is vertically reciprocated while the driving chain 15 is running. This reciprocation of the beam, depending on whether such movement is going on in upward or in downward direction, must necessarily result in an additional rotation of the main shaft 7 so as to increase or reduce the speed of rotation of such shaft. The reciprocation of the beam while chain 15 is running thus provides an additional or supplementary rotation to the shaft 7 whereby certain influences on the spinning or twisting operation is obtained.

I claim as my invention:

1. In a spinning and twisting machine a stationary frame, a spindle actuating shaft, a spindle carrying beam supporting said spindle actuating shaft and adapted to vertically reciprocate on the said stationary frame, an endless sprocket chain for operating the said actuating shaft, guiding sprockets carried by the said beam in fixed spaced relation with the spindle actuating shaft and adapted to reciprocate with the said beam and guiding sprockets on the said stationary frame in fixed spaced relation and not partaking in the beam reciprocation.

2. In a spinning and twisting machine a stationary frame, a spindle actuating shaft, a spindle carrying beam supporting said spindle actuating shaft and adapted to vertically reciprocate on the said stationary

frame, an endless sprocket chain for operating the said actuating shaft, guiding sprockets carried by the said beam in fixed spaced relation with the spindle actuating shaft and adapted to reciprocate with the said beam, guiding sprockets and a driving sprocket on the said frame in fixed spaced relation and not partaking in the beam reciprocation and a tensioning sprocket for securing the engagement of the said sprocket chain with the said reciprocating and non-reciprocating sprockets.

3. In a spinning and twisting machine a stationary frame, a spindle actuating shaft, a spindle carrying beam supporting said spindle actuating shaft and adapted to be vertically reciprocated on said stationary frame, and an endless sprocket chain for operating said actuating shaft, guiding and driving sprockets, said sprocket chain being passed around said guiding and driving sprockets which are fixed relative to the reciprocation of said beam and said sprocket chain having a portion running in a direction substantially parallel with the direction of the beam reciprocation and being in engagement with the spindle actuating shaft through the intermediary of said substantially parallel portion.

30. In testimony whereof I affix my signature.
JOHANN JACOB KEYSER.
